UNITED STATES PATENT OFFICE.

NORMAN W. SHERMAN, OF LAKE CITY, IOWA.

OIL-BURNER.

1,109,474.

Specification of Letters Patent.

Patented Sept. 1, 1914.

Application filed May 15, 1914. Serial No. 838,723.

To all whom it may concern:

Be it known that I, NORMAN W. SHERMAN, a citizen of the United States, residing at Lake City, in the county of Calhoun 5 and State of Iowa, have invented certain new and useful Improvements in Oil-Burners, of which the following is a specification.

My invention relates to improved hydro-carbon burners and has for its primary 10 object to provide a burner that is simple as to construction, inexpensive to manufacture and consumes very little fuel.

An important object of my invention is to provide a burner of the character described in which the oil is heated prior to 15 becoming ignited so that a gaseous vapor is provided, that when ignited produces intense heat, said heating of the oil being permitted by a novel means forming a part 20 of this invention and which consists of a pan or tray in which some of the oil is to be placed and ignited, certain pipes forming a part of the device and that lead to the burner being disposed within the pan 25 so as to become thoroughly heated.

My invention further aims to improve devices of the character described so as to render them more practical, reliable and efficient in operation, inexpensive to 30 operate and manufacture and simple as to construction.

The above and additional objects are accomplished by such means as are illustrated in the accompanying drawings, described in 35 the following specifications and then more particularly pointed out as claimed.

With reference to the drawings, wherein I have illustrated the preferred embodiment of my invention as it is reduced to 40 practice, and throughout the several views of which similar reference numerals designate corresponding parts: Figure 1 is a top plan view of my improved burner, Fig. 2 is an end elevation, Fig. 3 is a side elevation, Fig. 4 is a longitudinal sectional view partly in elevation of the burner, Fig. 45 5 is a transverse sectional view taken on line 5—5 of Fig. 1, and Fig. 6 is a horizontal sectional view showing the arrangement of 50 pipes that are positioned within the heating or starting pan.

Referring to the drawings by characters of reference the numeral 1 designates an approximately horizontal feed pipe that is 55 connected to a suitable source of fuel sup-

ply, not shown, at one end and at its other end by means of a T-coupling 2, is connected with curved couplings 3 and 4 which couple the rear ends of horizontal spaced and parallel inner heating pipes 5 and 6. 60 The inner heating pipes 5 and 6 are arranged in a horizontal plane and parallel to each other, on opposite sides of the feed pipe 1. U-couplings 5' connect the inner heating pipes 5 and 6 at the other front 65 ends with horizontal outer heating pipes 7 and 8 that are slightly spaced from the inner heating pipes 5 and 6 on the outer side thereof and arranged on opposite sides of the feed pipe 1. 70

Mounted in superposed relation to the pipes 5, 6, 7 and 8 in a horizontal plane are relatively large pipes 9 and 10 that are connected with the outer pipes 7 and 8 by means of curved couplings 11 and 12 that are connected with each other. Curved and upwardly extending couplings 13 are arranged in connection with the front ends of the pipes 9 and 10 and extend inwardly toward each other to a point adjacent the center of the 80 space comprehended between the relatively large pipes 9 and 10. Connected to the upper ends of the uppermost couplings 13 are parallel and horizontal burner pipes 14 that are slightly spaced from each other and 85 capped at each end as at 15 and 16. The caps 16 are each provided with a central aperture from which the flame or jet issues. Supporting legs 17 are secured by suitable fastening means 18 to the large pipes 9 and 10, adjacent to one end thereof. A rectangular pan 19 provided with upstanding and 90 inwardly curved supporting arms 20 is suspended from the pipes 9 and 10. The curved supporting arms 20 engage the pipes 9 and 10 and serve to support the pan 19 in such manner that the pipes 5, 6, 7 and 8 and the feed pipe 1 are disposed within the pan. The supporting arms 20 are arranged preferably on opposite sides of the pan. The 95 supporting legs 17 are of a length to extend to and end at the same plane with the under face of the pan. 100

In operation, a suitable quantity of hydro-carbon is placed within the pan and ignited 105 with the result that the pipes 5, 6, 7 and 8 also the pipes 9 and 10 become thoroughly heated. The hydrocarbon becoming heated partially vaporizes and when emitted from the openings in the caps 16 on the burner 110

pipes 14 is in the form of a gaseous vapor. The burner pipes 14 may be cleaned by removing the caps 15 and 16 at the ends thereof. In practice, the pan 19 is placed upon a table or like support and in combination with the legs 17 serves to support the burner in a reliable manner.

The pipes 5, 6, 7, 8 and feed pipe 1 take up partially the space within the pan and 10 it will be readily seen that when the hydrocarbon is ignited in the pan, the pipes will become heated in an expeditious manner. The hydrocarbon in being applied to the burner pipes flows through the pipes on 15 either side of the feed pipe within the pan and upwardly through the several couplings into the pipes 9 and 10, which in being relatively large act as compartments in which a comparatively large amount of heated hydrocarbon is stored.

It will be readily seen with reference to the foregoing description and accompanying drawings that I have provided a simple and inexpensive device that may be readily assembled and disassembled by reason of the 25 fact of the number of couplings and other detachable connections described previously.

The device is of a compact nature and is simple as to construction.

It will be readily seen that a reliable heating may be provided at a very low fuel consumption.

What is claimed is:—

An oil burner comprising a feed pipe, a plurality of parallel spaced and horizontal inner and outer pipes connected with the feed pipe and arranged on opposite sides thereof, relatively enlarged pipes arranged in parallel relation to each other and the inner and outer pipes and above the inner 40 and outer pipes, couplings connecting the enlarged and inner and outer pipes, burner pipes operatively connected with the enlarged pipes, and a rectangular pan to receive a suitable amount of hydrocarbon to 45 be burned and having the inner and outer pipes mounted therein, said pan being suspended from the enlarged pipes.

In testimony whereof I affix my signature in presence of two witnesses.

NORMAN W. SHERMAN.
